UNITED STATES PATENT OFFICE.

FRANK W. BECKWITH, OF DETROIT, MICHIGAN, ASSIGNOR OF ONE-HALF TO
HENRY W. FAIRBANK, OF SAME PLACE.

HINGE.

SPECIFICATION forming part of Letters Patent No. 322,239, dated July 14, 1885.

Application filed March 5, 1885. (No model.)

To all whom it may concern:

Be it known that I, FRANK W. BECKWITH, of Detroit, in the county of Wayne and State of Michigan, have invented new and useful 5 Improvements in Hinges; and I do hereby declare that the following is a full, clear, and exact description thereof, reference being had to the accompanying drawings, which form a part of this specification.

10 This invention relates to certain new and useful improvements in the construction of corner-hinges for trunks; and it consists in the peculiar combinations and the construction and arrangement of parts hereinafter more fully described and claimed.

Figure 1 is a perspective view of a corner of a trunk provided with my improved hinge. Fig. 2 is a section on the line $x x$, Fig. 1. Fig. 3 is a detail showing the inner faces of the two 20 leaves in perspective and the pintle removed. Fig. 4 is a vertical section through the hinges, open.

In the accompanying drawings, which form a part of this specification, A B represent the 25 two leaves of the hinge. The leaf A is provided with the two hook-knuckles C and with an intermediate hook-stud, D, the hook of which is outward, while those of the knuckles C project inwardly or toward the inner face of 30 the leaf.

The leaf B is provided with the double hook-knuckle E, the leaf being cut away on each side thereof, so as to receive the knuckles C of the part A.

35 F is the pin, preferably made of malleable iron, which, when the two parts of the hinge are engaged, is inserted beneath the hook-knuckles C and E and in front of the hook-stud D, while the ends of the pin rest upon 40 the leaf B.

To prevent the accidental displacement of the pin after it has been inserted in the hinge, I provide such pin with an arm, G, which is turned down upon the leaf B, and said arm is then bent so as to engage with a hook-stop, a , 45 upon the face of the leaf.

It will be observed that the double hook E is cut away sufficiently between the hooks so as to allow the hinge to open at right angles thereto, and that the shoulder of the hook-stud D, coming in contact with the body of the hook E, forms a stop which prevents the top of the trunk from falling clear back when opened.

In practice the parts A B are rigidly secured to the top and body of the trunk in the usual manner, so that when the cover is placed on top of the body the two parts of the hinges will engage. The pin is then inserted and secured as described.

It will be seen that in this construction the pin can readily be removed by disengaging it from the lock, and withdrawn, when the cover can be removed.

If desired, a hole may be made in the arm 65 of the pin, to be brought coincident with a hole in the leaf below, through which a nail can be driven.

If desired, the pin may be made straight and have a hole in its end through which to drive 70 a nail for the purpose of securing the pin, without departing from the spirit of my invention; but the construction herein described I consider the most preferable.

What I claim as my invention is—

1. A hinge consisting of the leaves A B, provided with suitable knuckles, C E, in combination with a removable pin, F, provided with an arm, G, and stop a , substantially as and for the purposes described.

2. A hinge consisting of the plates A B, provided with the knuckles C E and stud-hook D, in combination with a removable pin, F, adapted to be locked upon one of the leaves, substantially as and for the purposes specified. 85

FRANK W. BECKWITH.
